Mart, No. 4, vol. 8, P177, Feb. 25, 2011.
Sorarine, P1, Oct. 18, 2012.Primary Examiner — Michael A. Pratt
Assistant Examiner — Michelle E Wilson
(74) Attorney, Agent, or Firm — Irina Hass(57) **CLAIM**

The ornamental design for a cleaning article, as shown and described.

DESCRIPTION

FIG. 1 is a perspective view showing the new design for a cleaning article;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

The portions of the cleaning article in FIGS. 1, 3-7 shown in broken lines are included to show features that form no part of the claimed design.

1 Claim, 3 Drawing Sheets(56)
